US0D1023360S

(12) **United States Design Patent** (10) **Patent No.:** **US D1,023,360 S**
(45) **Date of Patent:** **** Apr. 16, 2024**

(54) **LIGHT STAND COMPONENT**

(71) Applicant: **Zhun-An Ma**, Ningbo (CN)

(72) Inventor: **Zhun-An Ma**, Ningbo (CN)

(**) Term: **15 Years**

(21) Appl. No.: **29/750,963**

(22) Filed: **Sep. 17, 2020**

Related U.S. Application Data

(62) Division of application No. 29/711,649, filed on Nov. 1, 2019, now Pat. No. Des. 897,019, which is a division of application No. 29/637,596, filed on Feb. 20, 2018, now Pat. No. Des. 869,718.

(57) **CLAIM**

The ornamental design for a light stand component, as shown and described.

DESCRIPTION

FIG. 1 is a top perspective view of a light stand component. FIG. 2 is a bottom perspective view of the light stand component of FIG. 1.

FIG. 3 is a front view of the light stand component of FIG. 1;

FIG. 4 is a back view of the light stand component of FIG. 1;

FIG. 5 is a left view of the light stand component of FIG. 1; FIG. 6 is a right view of the light stand component of FIG. 1;

FIG. 7 is a top view of the light stand component of FIG. 1; and,

FIG. 8 is a bottom view of the light stand component of FIG. 1.

The broken lines depict portions of the light stand component that form no part of the claimed design.

1 Claim, 6 Drawing Sheets
